(No Model.)

C. W. TURNER.
COTTON CLEANER.

No. 275,095.

Patented Apr. 3, 1883.

Fig. 1.

Fig. 2.

UNITED STATES PATENT OFFICE.

CHARLES W. TURNER, OF SENATOBIA, MISSISSIPPI.

COTTON-CLEANER.

SPECIFICATION forming part of Letters Patent No. 275,095, dated April 3, 1883.

Application filed January 2, 1883. (No model.)

To all whom it may concern:

Be it known that I, CHARLES W. TURNER, of Senatobia, in the county of Tate and State of Mississippi, have invented certain new and useful Improvements in Cotton-Cleaners, of which the following is a specification.

The object of my invention is to provide an apparatus for separating dust from seed cotton previous to its delivery to a gin, which shall be simple and inexpensive in construction, efficient in operation, and readily applicable to use in connection with any gin.

My invention therefore consists in a certain new organization of apparatus, as will herein-after be more fully described and claimed.

In the accompanying drawings illustrating my invention, Figure 1 is a side elevation of my improved apparatus; Fig. 2, a longitudinal section of the same, and Fig. 3 a transverse section on the lines 3 3 of Figs. 1 and 2.

The feed box or trough A is mounted on suitable legs or standards, B, and is provided at one end with a raised roof, C, the other end being left open to admit the cotton as it is supplied by an attendant. The bottom of the trough consists of an endless slatted feed-apron, D, mounted on rollers E and F, which are journaled by means of studs G in slots H H', formed in the sides of the feed-box. The apron may be further supported by means of strips I K, secured to the inner sides of the box under the upper slats of the apron. The ends of the studs G of the roller E are provided with heads or blocks L, which bear against wedges M, which in turn bear against the standards B, or against a strip or block secured to the side of the trough. By driving in or drawing out the wedges the roller E may be moved in the slots H, thus stretching and tightening or loosening the apron. An opening, N, normally closed by a hinged sloping board, O, may be formed at the front of the trough, through which uncleaned cotton may be removed by reversing the movement of the apron D or by tilting the entire apparatus. A drum or cylinder, P, provided with teeth or pins Q and stud-bearings R, is journaled in slots S S', formed in the sides of the feed-box under the roof C, by which arrangement the drum may be readily lifted out and replaced. When the drum is in position the slots S S' are closed by strips T, having cross-pieces U,

which may be bolted to the top of the sides of the box, and thus securely hold the studs R in their pivotal position at the bottom of the 55 slots. A shield, V, is placed under the drum at the end of the apron to prevent uncleaned cotton from falling into the gin. Beyond and a little above the drum is a supplemental chamber, W, in which is located an exhaust-fan, X, which revolves in the direction indicated by the arrow 1, causing a current in the direction of the arrow 2, downdraft being prevented by projecting boards or shelves Y. Above the fan is a flue, Z, through which 65 the current is discharged. Between the fan and the drum is stretched a wire screen, a, which is attached to the bottom of the side, b, of the chamber W, and a strip or board, c, is attached to the bottom of the screen, which 70 forms, with the incline c', a hopper, d. The screen is free to move to and fro, so that when the cotton accumulates in the hopper d it will force its way through into the gin-hopper located below; or the screen may be rigid, an opening 75 being left in the bottom of the hopper d. An opening, e, is also left between the screen and the end of the box for the ingress of air to the fan. Rigidly secured to the shaft of the drum P is a pulley, f, which is connected by means 80 of a belt, g, to the shaft of the gin (not illustrated) and by a belt, k, to the shaft of the exhaust-fan. On the opposite end of the shaft of the drum P is an eccentric or cam, l, for the purpose presently to be explained. 85 A bar, m, is pivoted to a block, m', on the side of box A, and is bent, as shown, to rest on the cam l, on which it is made to bear by means of a spring, o. A strap or bail, n, wound on a drum, n', may be attached to the end of 90 the bar to raise it away from the cam. The bar m carries a hooked rod, p, adjustable by means of a slide, q, provided with a set-screw, r. The hooked rod engages with a toothed wheel, s, on the roller F, against which it is 95 held by a spring, t, so that when the rod is lifted by the cam l the wheel s will be turned, and when the rod falls the hook will take a new hold; and by the continuance of these movements the roller F will be revolved, and 100 consequently the endless apron will travel forward. The wheel s is prevented from falling back by means of the spring-pawl u.

The apparatus, organized as above indicated,

having been placed over a gin and the belting having been arranged as shown operates as will now be explained.

The gin having been set in motion, the drum 5 P and exhaust-fan X will be rapidly rotated, and the endless feed-apron moved forward. The cotton, being supplied to the trough, is carried by the apron to the toothed drum, by which it is scattered and thrown against the 10 screen a, through which a strong current of air is drawn by the exhaust-fan X, and which draws through the screen dust and all other small foreign matter, and carries it away through flue Z, permitting the cotton, freed 15 from impurities, to fall into the hopper d, through which it is delivered to the gin.

I claim as my invention—

1. The combination of the feed-box, the feed-apron, the drum, the exhaust-fan, and a screen 20 interposed directly between the drum and the fan, so that the cotton may be scattered immediately in front of the screen and subjected to the exhaust-current while in a loose condition, substantially as set forth.
2. The combination of the feed-box having 25 slots S S', the drum journaled in said slots, the feed-apron, the exhaust-fan located in the chamber W, on the walls of which are secured the shelves Y for preventing downdraft, sub- 30 stantially as described.

3. In a cotton-cleaner, the combination of the feeding-apron, the exhaust-fan, the scattering-drum, the screen adapted to move to and fro between the drum and the fan, and the hopper d, formed by the incline c', and the strip 35 c on the bottom of the screen, substantially as described.

4. In a cotton-cleaner, the combination of the feeding apparatus with the exhaust-fan X and chamber W, provided with shelves Y, 40 to prevent downdraft, substantially as described.

5. In a cotton-cleaner, the combination of the apron D, the supports I K, the shield V, and the rollers E F, adjustable in slots H by 45 means of the wedges M, substantially as described.

6. The combination of the apron, the rollers, the cam, the bar carrying the adjustable hooked rod for turning the toothed wheel, the springs 50 for holding the rod upon the cam, and the hooked rod in engagement with the toothed wheel, substantially as described.

In testimony whereof I have hereinunto subscribed my name this 18th day of December, 55 A. D. 1882.

CHARLES W. TURNER.
